ARTIFICIAL LEG

Mario Capella Valenti, Barcelona, Spain

Application June 20, 1955, Serial No. 516,473

Claims priority, application France July 21, 1954

6 Claims. (Cl. 3—23)

This invention relates to an artificial leg with a corresponding foot for below-knee amputees or for deformed persons with considerable shortening of one lower extremity. In both cases the person equipped with the apparatus according to the invention is able to walk in a substantially normal way both over flat ground and over inclined or undulating ground.

This invention is an improvement in or development of the artificial foot described in the applicant's earlier Patent No. 2,446,042, which relates solely to an artificial foot comprising a hollow foot within which is a mechanism comprising two members which are articulated to one another and one of which is connected to the base of the artificial foot, while the other member is connected to a framework or assembly fixed to the leg or part thereof of the wearer. The said two members are interconnected through an articulated shaft and through a spring member associated with a braking or damping member.

The device according to the present invention comprises both foot and leg. The artificial foot is also hollow and contains the articulation mechanism consisting of two parts, one of which is fixed to the base of the hollow foot and the other of which is fixed to a framework or assembly associated with the artificial leg and fixed to the leg or part thereof of the wearer. The two parts of the foot are articulated to one another by means of a shaft disposed at the level of the normal ankle joint and are interconnected through the medium of a rod or spring-loaded connecting member which always returns the foot to the initial position after an oscillation of the foot during walking. The said mechanism also comprises a retarding or friction member which acts upon the said spring-like member in order to vary the action thereof accurately, constantly and operatively in dependence upon the inclination of the ground over which the wearer is walking. With this arrangement, the result is obtained that a person equipped with this artificial foot and leg can walk without difficulty over any type of ground whatever the inclination and nature thereof but does not undergo any more fatigue than would be felt by a normal person walking over this type of ground.

For a better understanding of the invention and to show how the same can be carried into effect, reference will now be made to the accompanying drawings, wherein:

Figure 1 is a side elevation of the combination forming the artificial foot and by which is fitted in this case to the leg of a below-knee amputee;

Figure 2 is a front view of the combination as shown in Figure 1;

Figure 3 is an exterior view, to a larger scale, of the mechanism within the hollow foot, in the same position as Figure 1;

Figure 4 is a front elevation of the last-mentioned mechanism;

2

Figure 5 is a vertical section thereof along the line V—V of Figure 4;

Figure 6 is an outer, part cutaway view from the side opposite to that shown in Figure 3;

5 Figure 7 is a section along the line VII—VII of Figure 5;

Figure 8 is a view similar to Figure 1 of a variant which is particularly suitable for persons having a considerable shortening of one leg;

10 Figure 9 is a plan view to a larger scale of the mechanism contained in the foot as shown in Figure 8, whilst Figure 10 is a section along the line X—X of Figure 9.

The form of construction illustrated in Figures 1 to 7 is particularly suitable for cases where the leg has been

15 amputated below the knee, and comprises a hollow foot formed by two parts 1—2 which contain the articulation mechanism of the said foot, which is in turn combined with a metal framework or assembly which forms the artificial leg proper and which is fixed to the wearer's 20 stump. This fixing assembly must obviously vary in dependence upon the conditions of each case, but in most cases the arrangement illustrated in Figures 1 and 2 will be used for amputees.

In order to ensure that the foot 1 can execute the 25 movements necessary for walking as if it were a normal foot, the two halves 3 and 5 of the mechanism are interconnected through the medium of a resilient rod or resilient connecting member formed by a hollow cylinder 10 articulated at 11 to the upper half 5 and having in its

30 interior a rod 12 terminating in a piston-like disc 13 actuated by a spring 14. The bottom of the rod 12 is articulated, through the medium of the shaft 15, to lugs 30 associated with a member 28 situated in the lower half 3. While the wearer is walking over flat ground, the 35 articulation shaft 15 remains stationary and serves as a bearing point for the spring-loaded rod 10, with the result that, when the wearer rests the foot on the ground while walking and when the spring 14 is compressed, the lower member 3 and foot 1 can return to the initial position 40 from the instant that this compression ceases.

In order to facilitate movement of the foot without tiring the wearer when he is walking up or down an incline, it is arranged according to the invention that the 45 articulation point 15 of the rod 12 can change its position in dependence upon the inclination of the ground and upon the direction of movement in order that the foot 1, when lifted clear of the ground during movement along an inclination, may not return of itself into the position as shown in Figure 1 but may remain in a position 50 which is always related to the direction of the ground. The result is therefore obtained that the wearer need not make an effort at every step to adapt the foot to the inclination of the ground even in the case in which, while the wearer is walking along a slope, the direction thereof or of walking changes abruptly.

To this end, there is disposed in the lower half 3 of the mechanism a short tubular piece 20 within which is a helicoidal spring 19, one of the ends of which is fixed to the cover 21 fixed to the member 3, and the other end 60 of which is fixed to a cover 22 having projections 23 engaging in recesses 24 in the short tubular piece 20.

The latter is fixed to the lower half 3 of the mechanism by means of a clamp 25 fixed to the base of the member 3 by screws 26 and adapted to be tightened by means of 65 the screw 27. The sole object of the clamp 25 is to act as a brake upon the cylinder 20. The pressure of the clamp 25 is always regulated in dependence upon the weight, height and muscular energy of the wearer in such manner that, when the wearer is walking over flat ground, the short tubular piece 20 does not turn but is 70 able to turn when the wearer displaces the centre of gravity of his body as occurs in walking up or down

inclines, when the piece 20 adapts the foot to inequalities of this type.

Also fixed in the piece 20 is a second clamp 28 which is tightened by means of the screw 29 and which has at its upper end lugs 30 to which the end of the rod 12 is articulated by means of the shaft 15. The clamp 28 determines the point of articulation 15 for the rod 12 and thus transmits to the foot 1 the movement which may be experienced by the body of the wearer according to the position of his centre of gravity, depending upon the steepness of the inclination of the ground over which he is walking. Moreover, by slackening the clamp 28 it is possible to adjust the mechanism, the tensioning of the spring 19 in the piece 20 being varied in dependence upon the muscular force of the wearer and as the complement of the pressure exerted upon the said piece 20 by the clamp 28 through the medium of the action of the screw 29.

One of the lugs 30 has a lateral projection 37 which, when the piece 20 turns with the clamp 28, slides upon a curved part 38 of the metal sheet forming the lower part of the mechanism. The curvature of the said metal sheet is such as to limit the movement of the articulation 30—15.

When the wearer is walking over flat ground, the piece 20 and the members associated therewith take up the position shown in Figure 5, and movement of the foot only occurs in one direction which is the direction of dorsal extension and which is due to the weight of the wearer's body at the instant of walking, while the return movement is due solely to the action of the spring 14.

On the other hand, when the wearer has to pass from flat to inclined ground, the displacement of the centre of gravity of the body mass exerts a greater force upon the movable part of the foot, so that the piece 20 together with the clamp 25 and helicoidal spring 19 causes the articulation shaft 15 of the spring-loaded rod 12 to vary its position automatically, the foot 1 thus being enabled to adapt itself to the inclination of the ground upon which it is resting. Thus, when the wearer lifts the foot clear of the ground, the sole of the foot remains not in a horizontal position but in a position which is always dependent upon the steepness of inclination of the ground, with the result that, when the wearer bears upon the foot again, he does not have to make any effort to adapt the foot to the inclination of the ground.

The artificial leg proper, that is to say the framework for fixing the artificial foot to the part 16 of the wearer's leg is formed by vertical members 31—32 on each side of the upward extension 8 of the foot. Fixed in the top of the members 31—32 is a short metal tubular piece 33 which is adapted to the leg below the knee. The free ends of the tubular piece 33 are articulated by means of shafts 34 corresponding to the rotational centre of the knee, to upper upwardly extending parts 35 which support a second brace 36 which fits the front half of the thigh somewhat above the knee, the brace 36 being fixed to this part of the thigh by means of straps 17—18.

The short tubular piece is a metal member produced from a moulding taken of the stump or terminal part of the wearer's leg 16, the said member 33 being such as to surround completely the stump and to be completely adapted to the contour thereof. On the other hand, the bottom of the tubular piece 33 is opened so that the leg 16 projects downwardly as indicated by the chain lines in Figure 1. In this way a very intimate fit is obtained of the tubular piece 33 upon the leg 16, the lower end thereof being left free so that the artificial foot can be worn with greater comfort.

The upper brace 36 is also made of metal and is also constructed from a moulding of the part to which the brace 36 is to be applied in order to obtain an exact fit. The central part of the front face of the brace 36 has a relatively large aperture having the double purpose of reducing weight and of permitting to the greatest pos-

sible extent the wearer's leg to perspire and to come into contact with the air.

In this way the artificial foot according to the invention can be conveniently fastened to the wearer's leg and thigh, and the wearer can walk normally on any type of ground whether the same is flat or inclined, hard or soft.

If this artificial foot is to be fitted to a person with a considerable shortening of one leg, the form of the fixing frame or artificial leg must be modified, and suitably the construction of the hollow foot is also slightly modified in order to adapt the same to the wearer's foot, this modification is illustrated in Figures 8 to 10.

The framework for fixing the artificial foot to the wearer's leg comprises a plate 45 which is adapted to the sole of the wearer's foot and which is articulated at 46 to the mechanism within the artificial foot. The plate 45 is connected to the foot by means of a brace 42 and extends upwardly to form another brace 43 which is fixed to the wearer's leg. In this case, the artificial foot comprises a hollow foot 41 which is similar to the part 1 of the foot as shown in Figure 1 and which contains the mechanism which is substantially identical with the mechanism as shown in Figures 3 to 7 and which operates in the same way as the last-mentioned mechanism.

The mechanism of the foot as shown in Figures 8 to 10 comprises a stamped sheet-metal framework 47 which is fixed to the sole of the hollow foot 41 and which has lateral lugs 48 by means of which the framework 47 is fixed to the lateral walls of the hollow foot 41. The framework 47 has secured to itself the clamp 25 which is arranged to rub against the tubular piece 20. The latter is also surrounded by a clamp 28 which in this case extends rearwardly, forming the articulation point 15 of the spring-loaded rod 10. The upper part 5 of the mechanism as illustrated in Figures 3 to 7 is substituted in Figures 8 to 10 by the plate 45 which is connected to the wearer's foot and with which is coupled the end of the spring-loaded rod 10. The articulation shaft 6 as shown in Figures 3 to 7 is substituted in this case by the articulation shaft 46 linking the plate 45 with the mechanism framework 47—48.

The operation of this form of construction is exactly as hereinbefore described with reference to Figures 3 to 7.

I claim:

1. An artificial leg comprising a hollow foot-shaped member having an upper and a lower part, an internal mechanism having an upper and lower part mounted within said foot-shaped member, said upper and lower parts of said internal mechanism being articulated to each other at the level of a normal ankle joint, a spring loaded rod articulated on the upper part of said internal mechanism, torsional spring means having one end connected to said lower part of said internal mechanism, a tubular member surrounding said torsional spring means to which the other end of said torsional spring means is connected, a clamp on the lower part of said internal mechanism in which said tubular member is rotatably clamped, a second clamp rotatably clamped on said tubular member and having a pivot thereon to which the other end of said spring loaded rod is articulated, an upwardly directed extension on the upper part of said foot member, and means thereon for attachment to a wearer's leg.

2. An artificial leg as claimed in claim 1 in which said second clamp has a plurality of lugs thereon and a shaft between said lugs forming the pivot for the articulation of the end of said spring loaded rod, a lateral extension on one of said lugs, and an arcuate portion on said lower part of said internal mechanism against which said extension bears for limiting relative movement of said upper and lower parts of said internal mechanism.

3. An artificial leg as claimed in claim 1 in which said attachment means comprise a cylindrical metal part on

said extension fitting around the part of a wearer's leg below the knee, and a metal brace on said extension for fitting around the thigh of a wearer's leg, said extension being articulated between said cylindrical metal part and said metal brace at a point corresponding to a wearer's knee.

4. An artificial leg as claimed in claim 3 in which said cylindrical metal part is shaped in the form of a wearer's leg from below the knee to above the end of the leg, whereby the lower end of the leg is incompletely enclosed.

5. An artificial leg as claimed in claim 3 in which said metal brace has a large aperture therein.

6. An artificial leg as claimed in claim 1 in which said means for attachment comprise a plate on said upper part of said internal mechanism for receiving the sole of the

foot of a wearer, and means for attaching said plate to the foot, ankle and lower leg of a wearer, said spring loaded rod being articulated to said upper part on the bottom of said plate.
